UNITED STATES PATENT OFFICE.

CHARLES H. ORCUTT, OF SPRINGFIELD, OHIO, ASSIGNOR TO JOHN W. PEARCE,
OF SAME PLACE.

FOLDING CHAIR.

SPECIFICATION forming part of Letters Patent No. 444,011, dated January 6, 1891.

Application filed July 5, 1890. Serial No. 357,800. (No model.)

To all whom it may concern:

Be it known that I, CHARLES H. ORCUTT, a citizen of the United States, residing at Springfield, in the county of Clark and State of Ohio, have invented certain new and useful Improvements in Folding Chairs, of which the following is a specification, reference being had therein to the accompanying drawings.

My invention relates to certain new and useful improvements in folding chairs; and the object is to provide such a chair with a locking device consisting, essentially, of a sliding member and a fixed member, the one being carried by one branch or part of the chair and the other by the other branch or part of the chair. One form of construction embodying this principle is shown and described in an application filed by me April 16, 1890, Serial No. 348,185.

In the accompanying drawings, forming a part of this specification, and on which like reference-letters indicate corresponding parts, Figure 1 represents a front view of my device in its folded position; Fig. 2, an edge view of the same with its sitting position indicated in broken lines; Fig. 3, a rear view of the chair in its sitting position; Fig. 4, a detail view of the spring-rod forming the sliding locking-bar and adjacent parts; Fig. 5, a portion of the rear leg at the hinge with the seat and adjacent parts in section, the chair being locked in its folded position; Fig. 6, a sectional view of the same in its sitting position; Fig. 7, a rear view of the locking parts; and Fig. 8, a section on the line $\alpha\alpha$ of Fig. 6, showing the preferred form of hinge.

The letter A designates the rear legs and back of a folding chair of the usual or any approved type, having the top B preferably connected to the cross-piece C by the usual back-strips D, and also having lower rounds E E'.

A seat-frame F, having the seat-bottom G of perforated veneer or other suitable material, and provided with a cross-piece H, of wood, metal or other material, on the lower rear end thereof, is pivotally connected at each end with the rear legs A, preferably by means of a dowel and socket I, as shown in Fig. 8. The front legs J are preferably secured to the front end of the seat-frame by

pivotal devices consisting of a plate and socket-cap, as already described in the application above referred to. The front legs are connected to the rear legs preferably by strips 55 K, of metal or other suitable material, conveniently curved as shown in Fig. 2 or otherwise, so as not to interfere with said cross-piece H when the chair is in its folded position. The seat-frame can thus be swung 60 about the pivotal point I, and I will now describe the locking mechanism, whereby it is locked in either its folded or sitting position.

The pivotal points I, forming the hinge, are located forward of the cross-piece C, and the 65 seat extends rearward so as to engage with the said cross-piece, which thus forms a stop for the seat when the chair is in its unfolded position. The seat itself acts as a lever, in which the weight of the person on the front 70 end presses the rear end up against the said cross-piece C, which is therefore preferably braced by the back-strips D.

The locking device consists of a spring rod or bar L, bent as shown in Fig. 4, or otherwise, so that when one end is mounted in the seat-frame the other end will extend to the rear and pass through a strip or piece M, depending from the cross-piece or otherwise. It will be seen that the said rod is accessible 75 from the front end of the seat-frame, so as to be actuated by the fingers to disengage it from its locking position by springing it back into the position shown in dotted lines in Figs. 1 and 4. Any convenient form of locking- 80 bar may be used, so long as it is accessible from the front end of the seat, and spring-actuated so as to engage with its locking socket or connection. This strip or piece M has a turned-up end M', and is preferably 85 of some rigid material, so that when the end of the spring L strikes on the said curved portion the rod will be sprung back till it reaches its locking position in the slot O, which is preferably somewhat larger than the 90 said rod, that it may not bind thereon under the strains put on the chair when tipped back on its rear legs only. The rod is conveniently guided by a groove in the seat-frame, and passes over the strip H, and is conveniently 95 supported at its rear end by a plate P, secured to the seat-frame. The position of the lock-

ing parts when the chair is locked in its sitting position is shown in Figs. 3, 6, and 7. The round E before mentioned is conveniently provided with a plate Q, having an opening therein, and screwed or otherwise fastened to the said round or cross-piece, so that when the seat assumes its folded position the rear end of the locking-bar will be pressed inward by said plate and slipped into the socket in the same, and thus lock the chair in its folded position, as shown in Figs. 1, 2, and 5. The rear end of the said bar is preferably rounded or beveled, so as to facilitate the action against the plate Q and strip M when it engages therewith. It will be seen that the spring of the metal of which the bar is formed tends to keep it always pressed outward. Any other means for causing this outward action may be employed as long as the bar is accessible from the front end of the seat.

If desired, I may dispense with the round E and lock the chair in its sitting position only, as before described.

25 The term "spring-rod" is used to cover any form of spring-locking means, whether in the form of an integral spring-rod or a rod actuated by a spring separate therefrom.

Having thus fully described my invention, 30 what I claim as new, and desire to secure by Letters Patent, is—

- 35 1. In a folding chair, the combination, with its back and its seat, the back being provided with an upper cross-piece having a socket and adapted to form a stop for said seat when folded, and also a lower cross-piece having a socket, and the seat being provided with a strengthening cross-piece near its rear end and pivotally connected to the said back,
- 40 of a spring-actuated locking-bar mounted in said seat and adapted to engage with the sockets in both cross-pieces, respectively, whereby the chair is locked in both its sitting and its folded position.

- 45 2. In a folding chair, the combination, with

its seat and its back provided with a cross-piece having a socket and adjacent to the rear end of said seat, of a spring locking-bar mounted in said seat so as to be accessible from the front end thereof and normally projecting outward and adapted to automatically enter said socket when the chair is folded, and thus lock it in its folded position.

3. In a folding chair, the combination, with its back and its seat, of an upper and a lower piece carried by said back adjacent to the rear end of said seat, and a locking device consisting of a sliding member and a fixed member, one member being carried by said seat so as to engage with the other member 60 carried by said upper piece, and also of a duplicate member carried by said lower piece, whereby the chair is locked in both its sitting and its folded position.

4. In a folding chair, the combination, with its seat, its back provided with an upper and a lower piece adjacent to the rear end of the said seat, and bearing or locking plates carried by said pieces, of a spring locking-bar mounted in said seat so as to be accessible 70 from the front end thereof and adapted to engage with said bearing or locking plates on the said pieces, respectively, whereby the chair is automatically locked in both its sitting and its folding position and unlocked by 75 manipulating said bar.

5. In a folding chair, the combination, with its seat and its back provided with a cross-piece adjacent to the rear end of the seat, of a spring locking-bar adapted to slide in and 80 out from the edge of said seat and accessible from the front end thereof and adapted to engage said cross-piece and lock the chair in its folded position.

In testimony whereof I affix my signature in 85 presence of two witnesses.

CHARLES H. ORCUTT.
